UNITED STATES PATENT OFFICE.

KENNETH E. STRAIN AND HOMER E. DAWSON, OF REYNOLDSBURG, OHIO.

AUTO-HEATER.

1,204,713.

Specification of Letters Patent. Patented Nov. 14, 1916.

Application filed March 8, 1916. Serial No. 82,989.

To all whom it may concern:

Be it known that we, KENNETH E. STRAIN and HOMER E. DAWSON, citizens of the United States, residing at Reynoldsburg, in the county of Franklin and State of Ohio, have invented certain new and useful Improvements in Auto-Heaters, of which the following is a specification.

Our invention relates to auto heaters designed particularly for use in cold weather to keep the passengers' feet warm and also to heat the interior of the car generally.

Our invention intends to utilize the portion of the air passing beneath the hood, which air is used as a cooling medium for the circulating water on water jacketed engines. We further may supplement this by causing this circulating air to encounter and pass around the exhaust pipe to additionally

heat it.

The main object of our invention resides in the combination with the floor board of an automobile having an opening therein, of a grid and deflector plate structure arranged to operate in conjunction with the opening to permit the flow of air into the interior of the vehicle or to exclude the same as may be desired, depending upon the atmospheric condition.

A further object of our invention resides in the provision of a register structure embodying a cowl structure co-operatively mounted with respect to the exhaust pipe, which cowl structure is provided with an opening arranged to permit the direct flow of air through the same when the deflector structure is in a position of closure over the register as a whole. However, when the deflector is in the opposite position, the cowl opening is covered to thereby deflect all of the heated air into the interior of the car.

The preferred embodiment of our invention is shown in the accompanying sheet of drawings, in which similar characters of reference designate corresponding parts, and in which:

Figure 1 is a sectional view showing a portion of an automobile engine and body with our heater structure applied thereto. Fig. 2 is a top view looking down onto the foot board structure as shown in Fig. 1. Fig. 3 is a view of the same structure but looking from the bottom, and, Fig. 4 is a cross section taken on line 4-4 of Fig. 3.

In Fig. 1, the automobile body is designated generally by the reference numeral 1

and is shown as being provided with an engine 2 having an exhaust pipe 3. The bottom of the vehicle is provided with a foot board shown at 4 and it is in connection with this foot board that our invention is applicable. This foot board is provided with a cut out portion or opening 5 which is covered by means of a grid shown at 6. To the underside of this foot board there is attached a cowl structure 7 which cowl is preferably formed of sheet metal bent to present two sides and a bottom as is shown. The bottom is cut out as at 8 to fit over the exhaust pipe 3 in the relation shown and is further provided with a cut out portion through the greater portion of its area as is shown at 9. Mounted in co-operative relation with this opening 9 and the grid structure 6 is a deflector plate 10 pivotally supported as shown at 11 to the cowl itself.

From the arrangement shown in Figs. 1 and 4, it will appear that when the deflector plate is in its lowered position, the draft of air coming through the radiator will circulate about the engine and the exhaust pipe and enter the interior of the vehicle. However, when this deflector plate structure is swung about its pivot to assume a position of closure with respect to the grid structure or as is indicated in dotted lines in Figs. 1 and 4, the draft of air is prevented from coming into the interior of the vehicle, but passes through the opening 9.

The deflector plate is preferably moved to lowered position by means of the locking member shown at 12, which member is provided with a series of ratchet teeth 12a. The locking member itself is pivotally supported as at 13 in connection with the deflector plate and pressure upon the foot plate 14 located on its outer end will force the deflector plate to the position shown in full lines in Figs. 1 and 4 and this position may be maintained by causing the last tooth 12 to engage the underside of the grid structure. However, this deflector plate is moved to this position against the pressure of a leaf spring as shown at 15, which leaf spring acts to urge the deflector plate to its elevated position or the position shown in broken lines. Therefore, release of the locking member from its position of engagement as is shown, will automatically move the deflector plate to the dotted line position.

From the foregoing description, it will be apparent that we have provided a very use-

ful structure for keeping the occupants of a motor vehicle warm during the winter months. Further, this device may be applied with comparative ease and further, does not render any of the working parts of the vehicle inoperative.

What we claim is:

1. The combination with the foot board of an automobile having an opening therein, of a grid covering said opening, a cowl coöperatively mounted with respect to the engine exhaust pipe, said cowl having an opening in its rear wall, and a movably supported deflector plate movable to assume position covering either the opening in said cowl or said grid.
2. The combination with the foot board of an automobile having an opening therein,

of a grid covering said opening, a cowl coöperatively mounted with respect to the engine exhaust pipe, said cowl having an opening in its rear wall, a pivotally supported deflector plate movable to assume position covering either the opening in said cowl or said grid, means for locking said plate in one of said positions, and spring means for urging said plate to assume the other position.

In testimony whereof we affix our signatures in presence of two witnesses.

KENNETH E. STRAIN.
HOMER E. DAWSON.
